H. GORY

UP ENDING DEVICE FOR ICE CAKES

Filed Jan. 10, 1924

Fig. 1.

Patented Nov. 4, 1924.

1,514,207

UNITED STATES PATENT OFFICE.

HARRY GORY, OF WYOMING, OHIO.

UPENDING DEVICE FOR ICE CAKES.

Application filed January 10, 1924. Serial No. 635,477.

To all whom it may concern:

Be it known that I, HARRY GORY, a citizen of the United States, and a resident of Wyoming, in the county of Hamilton and State of Ohio, have invented a certain new and useful Upending Device for Ice Cakes, of which the following is a full, clear, and exact description, reference being had to the accompanying drawings, forming part 10 of this specification.

The object of my invention is to provide a mechanical device for handling the large and heavy cakes of artificial ice as they are lifted from the freezing tanks and delivered to the refrigerating room for temporary storage prior to delivery to the customer.

Under the methods in use at present the cans containing the frozen blocks are lifted 20 from the freezing tank and the blocks of ice dumped on their sides and then pushed down an inclined chute into the cold storage room. The blocks of ice on their sides take up much more space than if the cakes 25 were raised and stored on end, but these cakes are exceedingly heavy and it is an arduous task requiring a good deal of strength to upend the cakes.

It is the object of my invention to provide mechanical means for accomplishing 30 this task, and it consists of that certain novel construction and arrangement of parts to be hereinafter particularly pointed out and claimed.

35 In the drawings,

Figure 1 is a side elevation of my apparatus.

Figure 2 is a plan view of same.

The floor of the tank room is indicated 40 at 1 and shown as supported on uprights 2, 2, suitably braced. Leading from this floor 1 is an inclined floor 3 descending to the floor level of the storage room and it is down this incline that the cakes of ice are 45 slid when dumped from the cans 4 in which the blocks are frozen.

Pivots mounted on supports 5 is the 50 holder 6 in which the cans are placed for dumping. This holder is constructed of sufficient width to hold the desired number of cans. In the present instance I have illustrated a holder of a size to hold five cans.

The holder when in upright position has 55 sides 7, 7, with partitions 8, and a bottom 9, and is open at the top. When in this up-

right position the cans are lifted by a crane from the freezing tank and deposited in the holder, and then the holder is tipped over into the position shown in Figure 1, with its upper edge resting on the incline 3. 60 The cans are held in the holder by lugs 10, but the ice blocks at once slide out of the cans down the incline onto a platform 12, which is on a level with the storage room floor. The blocks of ice slide across this 65 platform and up an inclined table 13 against a bumper beam 14 which is shod with a rubber cushion 15. The recoil from contact with this cushion causes the blocks to slide back until they rest against a rubber cushion 16, as indicated in dotted lines in Figure 1. To keep the cakes of ice separated and in position on the table, side strips 17 and partition strips 17^a are provided.

To prevent injury to the cakes when they 70 reach the table a rubber cushion 18 is secured along the front lower edge of the table.

The table is pivoted at 19 on the frame 75 work 20 and it is supported in inclined position by the piston rod 21 carrying a piston seated in the cylinder casing 22. This piston cylinder is pivotally mounted at the lower end on the support 23 and compressed 80 air is furnished through the pipe 24 to raise 85 the piston and with it the table into upright position. This air is controlled by a valve 25 in convenient position for the operator. At the upper end of the table a weight 26 is attached to the under portion 90 of the table by a flexible cord 27 running over a guide pulley 28. As soon as the cakes of ice are dumped and come to rest against the cushion 16, as above described, the operator turns on the air controlled by valve 95 25, the piston is lifted and the table raised to vertical position as indicated in dotted lines in Figure 1 and the blocks of ice are thus upended on the platform 12, whence 100 they are easily pushed into the storage room for shipment.

In this way the blocks are readily and easily transferred from the tank room to the storage room without the need of lifting manually the heavy blocks and in much less time than required heretofore. Also there is no liability of the blocks sliding out of control in dumping from the cans and becoming damaged by violent contact with each other and there is no danger to operatives from 110

the sliding blocks. The cakes of ice are under perfect control without any exertion on the part of operatives. As soon as the blocks of ice are discharged from the table, 5 the weight draws back the table into its original inclined position, ready for the next supply.

Having thus described my invention, what I claim as new and desire to secure by Letters Patent, is:—

1. In a device of the character specified, the combination with fixed platforms at different heights and an intermediate inclined way, of a table pivotally mounted alongside the lower platform, means for holding said table oppositely inclined to check the cakes of ice which slide down the inclined way and across the lower platform, and means to raise said table into substantially upright position to up end the cakes on the lower platform.

2. In a device of the character specified, the combination with platforms at different heights and an intermediate inclined way, 25 of a table pivotally mounted alongside the lower platform, a rod pivoted to said table to hold same in an oppositely inclined position to check the cakes of ice which slide down the inclined way, and means for actuating the rod to raise the table into substan-

tially upright position to up end the cakes on the lower platform.

3. In a device of the character specified, the combination with platforms at different heights and an intermediate inclined way, of 35 a table pivotally mounted alongside the lower platform, a piston rod pivoted to said table to hold same in an oppositely inclined position to check the cakes of ice which slide down the inclined way, a cylinder closed at the lower end pivoted to the frame, with piston therein to which the piston rod is connected, and compressed air connections to operate the piston to raise the table into upright position.

4. In a device of the character specified, the combination with platforms at different heights, and an intermediate inclined way, of a table pivotally mounted alongside the lower platform, means for holding said table oppositely inclined to check the cakes of ice which slide down the inclined way, with a cushioned bumper to stop the movement, and a cushion along the side of the lower platform to receive the ice cakes, and means to raise the table into substantially upright position to up end the cakes on the lower platform.

HARRY GORY.
